IRONING TABLE LEG UNIT

Donald J. Munson, Minneapolis, Minn., assignor to The
J. R. Clark Company, Spring Park, Minn., a corpora-
tion of Minnesota

Filed Dec. 31, 1964, Ser. No. 83,242

Term of patent 14 years

(Cl. D49—1)

FIG. 1

FIG. 2

FIG. 1 is a perspective view of an ironing table leg unit, embodying my new design;

FIG. 2 is an enlarged fragmentary top plan view of the lower front portion thereof;

FIG. 3 is a side elevational view of the unit;

FIG. 4 is an enlarged fragmentary top plan view of the lower rear portion thereof;

FIG. 5 is an enlarged fragmentary rear elevation view thereof taken on line 5-5 of FIG. 3;

FIG. 6 is an enlarged fragmentary cross-sectional view thereof taken on line 6-6 of FIG. 5; and

FIG. 7 is an enlarged fragmentary cross-sectional view thereof taken on line 7-7 of FIG. 5.

The broken lines shown in the drawing are for illustrative purposes only.

I claim:

The ornamental design for an ironing table leg unit, as shown and described.
